UNITED STATES PATENT OFFICE.

A. JUDSON CHAPEL, OF ARKANSAS CITY, KANSAS.

CAR-COUPING.

SPECIFICATION forming part of Letters Patent No. 297,765, dated April 29, 1884.

Application filed January 23, 1884. (No model.)

To all whom it may concern:

Be it known that I, A. JUDSON CHAPEL, a citizen of the United States, residing at Arkansas City, in the county of Cowley and State of Kansas, have invented certain new and useful Improvements in Automatic Car-Couplings, of which the following is a full, clear, and exact description, reference being had to the accompanying drawings, forming a part 10 of the specification, in which—

Figure 1 is a plan view of my improved automatic car-coupling, representing the draw-bars as coming together in the act of coupling. Fig. 2 is a plan view of the link. Fig. 15 3 is a longitudinal vertical section of the draw-bar, showing a side view of the coupling-pin. Fig. 4 is a front elevation of a draw-bar with the coupling-pin in place and the lever for raising and lowering the same. Fig. 5 is a 20 side view of the link, showing its beveled ends for engaging the beveled outer ends of the tongues of the pins to lift the latter; and Fig. 6 is a horizontal sectional view of the coupling-pin, and shows, also, the shape of 25 the coupling-pin holes in the top and bottom faces of the draw-bar.

My invention relates to improvements in automatic couplers; and it consists in the peculiar construction and arrangement of the 30 parts, as hereinafter more fully set forth, and pointed out in the claims.

The draw-bars A of my improved automatic car-coupling are of the ordinary construction, with flaring mouths to receive the link in 35 coupling cars, the only difference in construction between my construction and the ordinary form of draw-bar being the form of the holes in the upper and lower faces of the draw-bar, as shown in Fig. 6, which conform to 40 the peculiar shape of the coupling-pin, which is also shown in horizontal section in said figure.

B B' D represent the coupling-pin, which passes through the correspondingly-formed 45 holes in the upper and lower faces of the draw-bar and through the link, and consists of a half-rounded head, B, composed of sides a a, (see Fig. 6,) a circular arc, b, two shoulders, c c, and a central tongue or flange, D, with flat 50 sides, and its front edge beveled from above downward and backward to receive the double-beveled end of the link C in coupling, and lift the pin, which afterward falls in one of the 55 openings in the link and couples the cars auto-

matically. The coupling-pin B D is also provided with a horizontal cap, B'. It has been stated above that the holes in the upper and lower faces of the draw-head are of the same shape precisely as a cross-section of the coupling-pin, to receive the latter as it passes 60 through the link, so that when the car is coupled the shoulders c c of the coupling-pin B B' D will bear against corresponding shoulders, c' c', in the holes in the upper and lower faces of the draw-bar, and prevent the larger 65 half-rounded part B of the coupling-pin from turning on its axis in passing over the curves of the road, and thereby prevent all friction or binding of the tongue D in the holes D' in the upper and lower faces of the draw-bars, 70 which arise in a similar construction of coupling-pin which is old, in which the part B is made cylindrical and provided with a beveled tongue, whereby the coupling-pin is raised by the link in coupling. Preferably, to the top 75 face of the draw-bar is pivoted in suitable uprights a lever, x, which extends out to one side of the car, and is secured to the enlarged part of the coupling-pin B by an eyebolt, through which the inner end of the lever x 80 passes, whereby the coupling-pin can readily be raised and lowered, when desired.

Having thus fully described my invention, what I claim as new, and desire to secure by Letters Patent, is—

1. In an automatic car-coupling, the combination, with the link C, double beveled at its ends, as shown, and a draw-bar, A, provided with holes in its upper and lower faces of the same configuration as a horizontal section of the coupling-pin, of a coupling-pin composed of a head, B, having sides a a, circular arc b, shoulders c c, and a central tongue or flange, D, having its outer edge downwardly and rearwardly beveled near its lower end, 90 substantially as shown and described.

2. The combination, with the draw-bar A and coupling-pin B B' D, having an eyebolt secured to its rear end, of the lever x, fulcrumed in studs secured to the draw-bar, and 95 having its inner end passing through the eye of the eyebolt, substantially as shown and described.

A. JUDSON CHAPEL.
